UNITED STATES PATENT OFFICE.

HARRY J. EISENBERG, OF MONTGOMERY, ALABAMA.

DESIGN FOR A BOTTLE.

Application filed September 23, 1925. Serial No. 14,879. Term of patent 14 years.

To all whom it may concern:

Be it known that I, HARRY J. EISENBERG, a citizen of the United States, residing at Montgomery, in the county of Montgomery and State of Alabama, have invented a new, original, and ornamental Design for Bottles, of which the following is a specification, reference being had to the accompanying drawing, forming part thereof.

Figure 1 is a side elevation of a bottle, showing my new design.

Figure 2 is a sectional view on line 2-2 of Figure 1.

Figure 3 is a sectional view on line 3-3 of Figure 1.

I claim:

The ornamental design for a bottle, as shown.

HARRY J. EISENBERG.
